UNITED STATES PATENT OFFICE.

ROBERT HEAD, OF NEW YORK, N. Y., ASSIGNOR TO THE AEOLIAN COMPANY, A CORPORATION OF CONNECTICUT.

PHONOGRAPH AND THE LIKE.

Application filed October 29, 1917. Serial No. 199,043.

To all whom it may concern:

Be it known that I, ROBERT HEAD, a citizen of the United States, residing at city, county, and State of New York, have invented new and useful Improvements in Phonographs and the like, of which the following is a specification.

My present invention relates particularly to means for obtaining a constant-speed electric-drive in phonographs and similar instruments, in spite of line fluctuations in the supply current for the motor.

The drawings illustrate one of the embodiments my invention is adapted to take. Fig. 1 is a fragmentary side-elevation of a phonograph equipped with electric-driving means within my invention; Fig. 2 is an underneath plan view of Fig. 1; and Fig. 3 is an enlarged detail from Fig. 1 showing

some of the parts in vertical cross-section.

Describing now the devices of the drawings, 1 is the deck of a phonograph; 2 is the turn-table supporting the disc-record 3; 4 is the turn-table spindle rotating in an upper-bearing 5 and supported on a lower-bearing 6.

7 is an electric motor whose shaft carries the worm 8, which in turn drives the worm-wheel 9, the latter loosely surrounding the turn-table spindle. The worm-wheel 9 is preferably made of fiber or equivalent functioning material and is held between a pair of friction-disks 10 and 11, the former being pinned to the spindle and the latter being splined thereto and frictionally pressed against the fiber worm-wheel 9 by the coiled compression-spring 12 whose tension can be adjusted by adjusting the collar 13 up or down.

14 is a well-known type of centrifugal governor driven from the turn-table spindle by the usual connection comprising a worm-wheel 15 on the turn-table spindle and a worm 16 on the spindle of the governor. 17 is the usual endwise, movable friction-disk of the governor which bears against the adjustable stop 18 when the turn-table spindle is up to speed and otherwise operates to govern the maximum speed of the turn-table.

50 Thus the motor 7 drives the worm-wheel 9 which in turn frictionally drives the turn-table spindle 4 at a maximum speed which is determined by the adjustment of the stop 18 of the governor 14.

55 The arrangement is such that the motor

has an excess speed which is much more than enough to drive the turn-table up to speed. This excess speed expends itself in making the worm-wheel 9 slip on the discs 10 and 11. The result is that any fluctuations in the supply-current for the motor do not affect the speed of the turn-table. If the voltage goes up making the motor run faster, it merely causes the work-wheel 9 to slip faster. If the voltage goes down making the motor run slower, it merely causes the worm-wheel to slip less and continues to drive the turn-table spindle up to its maximum speed determined by the governor.

Thus I have provided practical means which will drive a rotary part at a constant speed from an electric-motor unaffected by the inevitable fluctuations in the motor speed due to the line-current.

Having thus described my invention, what I claim is:

1. The combination of a driven rotary member, means operative at all times to govern the maximum speed of said member, a motor having a speed which is greater than that required to rotate said member at its maximum governed speed, and a slip connection between the motor and the driven member, which connection is so adjusted as to provide a slippage at all times between the motor and the driven member and compensate for variations in the excess speed of the motor over the speed of the driven member, due to fluctuations in the speed of the motor.

2. In a phonograph, the combination of a turntable shaft, means operative at all times to govern the maximum speed of said shaft, a motor having a speed which is greater than that required to rotate the turntable shaft at its maximum governed speed, and a slip connection mounted on the turntable shaft and forming a drive between the motor and the turntable shaft, said connection being so adjusted as to provide a slippage at all times between the motor and the turntable shaft and to compensate for variations in the excess speed of the motor relatively to the speed of the turntable shaft, due to fluctuations in the speed of the motor.

3. In a phonograph, the combination of a turn-table shaft, a governor connected thereto and operative at all times to determine the maximum speed of such shaft, a motor

having a speed in excess of that required to rotate the turntable shaft at its maximum speed, a slip connection between said shaft and motor which is so adjusted as to provide 5 slippage at all times between said shaft and motor, said connection comprising a gear loosely mounted on said turn-table shaft and connected to the motor, and friction disks fixed on said shaft to rotate therewith and 10 coacting with the opposite sides of said gear.

4. In a phonograph, the combination of a turn-table shaft, means operative to govern at all times the maximum speed thereof, a 15 motor having a speed in excess of that required to drive the turn-table shaft at its maximum speed, and a slip connection be-

tween said shaft and motor which is so adjusted as to provide a slippage at all times between said shaft and motor, said connection comprising a gear driven by the motor and loosely mounted on the turn table shaft, a friction disk fixed to the turn-table shaft and engaging one side of said gear, a second friction disk movable axially on said shaft and engaging the opposite side of said gear, and a spring encircling said shaft and exerting pressure between said friction disks and said gear.

In testimony whereof, I have signed my name to this specification this 27th day of October, 1917.

ROBERT HEAD.
